UNITED STATES PATENT OFFICE.

ALVA WATTS, OF NEW BRIGHTON, PENNSYLVANIA, ASSIGNOR OF ONE-THIRD TO JOHN M. RICHARDS AND ONE-THIRD TO JAMES T. MOLTRUP, OF BEAVER FALLS, PENNSYLVANIA.

BOTTLE-MAKING MACHINE.

No. 913,996.

Specification of Letters Patent.

Patented March 2, 1909.

Application filed February 7, 1908. Serial No. 414,779.

To all whom it may concern:

Be it known that I, ALVA WATTS, a citizen of the United States, residing at New Brighton, in the county of Beaver and State of 5 Pennsylvania, have invented new and useful Improvements in Bottle-Making Machines, of which the following is a specification.

This invention relates to bottle making machines and more particularly to a machine 10 for dressing or grinding the tops of the bottle necks.

The invention has for one of its objects to improve and simplify the construction and 15 operation of machines of this character so as to be comparatively simple and inexpensive to construct and keep in repair, thoroughly reliable and efficient in use, and whereby a large number of bottles can be ground in one operation.

20 A further object of the invention is to provide a machine by which a large number of bottles can be ground at one time and with comparatively little expense and which is provided with bottle holders which can be 25 quickly and easily taken out when the bottles are finished and replaced after they have been re-charged.

Another object of the invention is to provide a head having provision for receiving a 30 plurality of holders, said head being arranged on a suitably driven shaft disposed in operative relation to the grinding wheel or stone.

A still further object of the invention is the 35 employment of a simple form of means for clutching and unclutching the head carrying shaft with respect to the power shaft so that the former can be held stationary while taking out and putting in the bottle holders.

With these objects in view and others, as 40 will appear as the description proceeds, the invention comprises the various novel features of construction and arrangement of parts which will be more fully described hereinafter and set forth with particularity 45 in the claims appended hereto.

In the accompanying drawing, which illustrates one of the embodiments of the invention, Figure 1 is a front view of the machine. Fig. 2 is a plan view of a bottle-carrying 50 head drawn on an enlarged scale. Fig. 3 is a central vertical section of the head. Fig. 4 is a transverse section on line 4—4, Fig. 3. Fig. 5 is a perspective view of one section of a bottle holder.

55 Similar reference characters are employed

to designate similar parts throughout the several figures of the drawings.

Referring to the drawing, A designates a supporting frame of any suitable construction and comprising in the present instance 60 uprights 1, a top cross-piece 2, intermediate cross-pieces 3, and a table 4. Mounted above the table is a basin 5 in which rotates the grinding wheel or stone 6. The stone 6 is keyed to a vertical driving shaft 7 having 65 its lower end mounted in a step bearing 8 in any approved manner and steadied in its upper end in a bearing box 9 on the top cross-piece 2. On the upper portion of the shaft 7 is a pulley 10 for receiving a belt whereby the 70 machine is driven.

Disposed parallel with the driving shaft 7 are a plurality of head carrying shafts 11 mounted in bearings 12 on the intermediate cross-pieces 3. In the present instance two 75 of such shafts are shown, but it is to be understood that any desired number may be employed. On the upper ends of the shafts 11 are friction wheels 13 that peripherally engage with a small friction wheel 14 on the 80 driving shaft 7, whereby the head carrying shafts 11 are frictionally driven at a somewhat slower speed than the stone driving shaft 7. In order to hold the shafts 11 in inoperative position when the bottle holders 85 are to be removed, each shaft is provided with a lever carrying a counterbalance weight. Disposed inwardly from the uprights 1 and secured to the cross-pieces 3 are posts or standards 15 on each of which is a 90 lever 16 fulcrumed at 17 and having at its outer end a weight 18. The inner end of the lever is bifurcated or otherwise formed to engage around the adjacent head carrying shaft 11, as indicated by 19. On the shafts 95 11 are fixed collars 20 under which the bifurcated ends 19 of the levers engage. The shafts 11 are clutched to the friction wheels 13 so that the former can be idle during the taking out and placing of the bottle holders 100 in the heads on the shafts 11. These clutches may be of any approved construction and in the present instance, each comprises a disk 21 keyed to its respective shaft 11 and provided with a diametrically extending rib 22 on its under surface adapted to engage in a diametrical slot in the upper end of the hub 23 of the adjacent friction wheel 13. Thus, upon raising the shafts 11 and by pulling 105 down on the outer ends of the levers, the

110

ribs 21 are disengaged from the clutch members on the wheels 13, whereby the wheels rotate idly. The levers can be held in depressed position for holding the shafts out of connection with the wheels 13 in any suitable manner, as for instance by buttons 16' on the uprights 1, so that the bottle holders can be conveniently taken out of and placed in the heads B. In order to prevent the bottles from being ground beyond a certain extent, stops in the form of adjustable collars 24 are secured to the shafts 11 to engage with the lower bearings 12 for the latter when the bottles have been ground to the limit. When the stops thus bear on the bearings 12, the machine can continue to operate indefinitely without grinding the bottles, this being an important feature, since the constant care of the operator is unnecessary so that he can be engaged in other work such as filling holders to get them ready for another charging of heads.

The holders on the shafts 11 each comprise a suitably shaped body designated generally by B. This body, in the present instance, is cast cruciform with its arms 25 hollow from their outer extremities to the central portion or hub 26. By having the arms 25 open at their outer ends, the individual bottle holders can be taken out and inserted in a simple and easy manner. The arms 25 are open at the bottom and are provided with plates 27 that are secured in place by bolts 28 passing through the plates and bored bosses 29 on the sides of the arms, the said bolts being provided with wing nuts 30. The plates 27 are each provided with a centrally disposed longitudinal slot 30' through which the necks of the bottles protrude, so as to be operated on by the grinding wheel 6. The shafts 11 are secured in the hubs 26 in any suitable manner. Each bottle holder is composed of two sections 31 and 32 in which are formed cells or chambers 33, those of one section registering with the cells or chambers of the other section so as to receive the bottles to be ground. Each holder is preferably in the form of a parallelepiped and is adapted to slide into its respective arm 25 of the head 13 inwardly and outwardly through the open end thereof and the bottom of the holder rests on the plate 27 of the said arm. A top clamping plate 34 is arranged in each arm to bear on the top of the bottle holder and this plate is clamped in position by a screw 35 passing upwardly through the arm and fitted with a hand wheel 36. To clamp the two sections of the bottle together while the latter is in position on the head, a side clamping plate 37 is employed to bear against the section 32 as shown in Fig. 4, and this clamping plate is provided with a screw 38 having a hand wheel 39.

From the foregoing description, taken in connection with the accompanying drawing,

the advantages of the construction and of the method of operation will be readily apparent to those skilled in the art to which the invention appertains. In operation, the bottles to be ground are arranged in the holders and the latter are slid radially into the several arms or chambers in the heads 13, the latter being stationary by reason of the head-carrying shafts 11 being unclutched from the friction wheels 13. As each bottle holder is placed in a head, the plates 34 and 37 are firmly clamped against the bottle holder so that the bottles in the latter are held from moving. After all the bottle holders are in position, the levers 16 are actuated so that the shafts 11 are clutched to their respective friction wheels. The shafts are thus rotated and the necks of the bottles held into engagement with the grinding wheel 6. After the bottles are properly compressed, the outer ends of the lever 16 are disposed so that the shafts 11 may be unclutched. The bottle holders are then taken out and the finished bottles removed and the heads again charged in the manner just described. Any suitable hopper may be used in connection with the machine for supplying abrasive material to the grinding stone to increase the cutting power of the latter. It will be seen that a large number of bottles can be quickly and uniformly dressed with a minimum of labor and expense.

I have described the principle of operation of the invention, together with the apparatus which I now consider to be the best embodiment thereof, I desire to have it understood that the apparatus shown is merely illustrative and that such changes may be made when desired, as are within the scope of the claims.

Having thus described the invention, what I claim is:

1. In a machine of the class described, the combination of a grinding element, a shaft for rotating the same, a shaft disposed parallel with the first-mentioned shaft, a driving mechanism between the shafts which includes a clutch, and a bottle carrying head on the second shaft disposed in coöperative relation with the grinding element.

2. In a device of the class described, the combination of a supporting structure, a grinding element thereon, a vertical driving shaft for the element, bottle carrying heads disposed in coöperative relation with the grinding element, removable bottle holders in the heads, vertically movable shafts on the structure for supporting the heads, gearing between the driving shaft and head supporting shafts, a clutch device operated by the longitudinal movement of the shafts for rendering the latter idle, and means for holding the shafts in idle position.

3. In a machine of the class described, the combination of a grinding element, a verti-

- 5 cally movable shaft, a bottle carrying head thereon, removable bottle holders in the head, means for driving the shaft, a clutch for disconnecting the shaft from the driving means, and dependent upon the longitudinal movement of the shaft, and means for holding the shaft unclutched from the driving means. 55
- 10 4. In a machine of the class described, the combination of a grinding element, a vertically movable shaft, a member for supporting a plurality of bottles attached to the shaft, and means for limiting the movement of the shaft in a direction toward the grinding element. 60
- 15 5. In a machine of the class described, the combination of a grinding element, a vertically movable shaft, a structure thereon for removably supporting a plurality of bottles or similar articles, a driving means for the shaft, a clutch between the means and shaft which is opened or closed by the longitudinal movement of the latter, and a counterbalancing weight for holding the shaft unclutched. 65
- 20 6. In a machine of the class described, the combination of a grinding element, a supporting frame, bearings thereon, a vertical shaft movably mounted in the bearings, a structure on the shaft for holding a plurality of articles to be ground, a lever mounted on the frame and connected with the shaft for moving the same longitudinally, a counterbalancing weight on the lever for holding the shaft in adjustable position, a driving means 70 for the shaft, and a clutch for connecting and disconnecting the shaft with respect to the driving means. 75
- 25 7. In a machine of the class described, the combination of a head having a chamber, a removable bottle holder in the chamber, and means for clamping the holder in the head. 80
- 30 8. In a machine of the class described, the combination of a rotatable head having a plurality of radial chambers provided with bottle neck receiving slots in their bottoms, bottle holders movable radially into and out of the chambers of the head, and means for clamping the holders in the chambers. 85
- 35 9. In a machine of the class described, the combination of a rotatable head having a chamber slotted at its bottom, a two-part bottle holder removably mounted in the chamber, and a clamping means for holding the parts of the holder together and for clamping the holder in the head. 90
- 40 10. In a machine of the class described, the combination of a rotatable holder having a chamber open at one end and slotted at its bottom, a bottle holder having a plurality of bottle receiving cells from which the necks of the bottles protrude, said holder being movable longitudinally in the chambered head and arranged therein with the necks of the bottles extending through the slot of the head, clamping plates engaging the sides of the holder, and clamping screws extending through the walls of the head for clamping the holder in position by the said plates. 95
- 45 11. In a machine of the class described, the combination of a chambered member having an opening at one end and provided with a slotted bottom, with a bottle holder 70 slidable longitudinally in and out of the open end of the member and arranged with the necks of the bottles projecting through the 75 slotted bottom of the member.
- 50 12. In a machine of the class described, the combination of a chambered head open at one end and at its bottom, a slotted plate secured to the head to form a bottom therefor, a bottle holder removably mounted in the head, and means for clamping the holder against the said bottom plate. 80
- 55 13. In a machine of the class described, the combination of a member having a rectangular chamber, a bottle holder slidably mounted in the chamber, means for clamping the holder in place, said holder comprising sections having registering cells or chambers for receiving a plurality of bottles. 90

In testimony whereof, I affix my signature in presence of two witnesses.
